Filed Apr. 30, 1957, Ser. No. 656,093
7 Claims. (Cl. 330—4)

This invention relates to devices for amplifying or generating electromagnetic energy and more particularly to a device employing solids, liquids or gases for amplifying or generating microwave energy by stimulated emission of radiation.

Generally speaking, "masers" may be defined as devices for amplifying or generating wave energy by utilizing molecules in the excited state of a microwave transition. Interaction between these excited molecules and a microwave field produces additional radiation and hence amplification by "stimulated emission." The operation of masers, such as the one described herein, is dependent upon the fact that in paramagnetic materials the electrons surrounding the nucleus of an atom may be in different energy states. These energy states may be thought of as arising from the interaction of the electron spins with internal or external fields. We may therefore refer to them as electron "spin states." The energies of the electron spin states may be varied by an external magnetic field. Therefore, the energy difference between two given electron spin states is determined by the magnitude of the external magnetic field.

If a paramagnetic material having an excess electron spin population in a higher energy state is placed in a resonant cavity and if electromagnetic energy of appropriate frequency is fed into the cavity, the electron spins in the higher energy state will revert to a lower energy state, thereby releasing energy which amplifies the signal fed into the cavity. In order to release the energy of the electron spins in the upper state to produce amplification, however, the original signal fed to the cavity must be of an appropriate frequency which is determined by the difference in the energy levels of electron spins in the upper and lower states; and this energy difference is, in turn, dependent upon the strength of the external magnetic field applied to the paramagnetic material. Thus, by varying the strength of the external magnetic field, the frequency at which the paramagnetic material will release its energy in the resonant cavity may be varied also. If the frequency of the electromagnetic signal fed into the cavity is not of the correct frequency to be amplified or if no signal is introduced at all, the electron spins in the upper energy state, by interaction with their surroundings, will revert to a lower energy level over a time interval called the "spin-lattice relaxation time."

It is an object of this invention to provide a new and improved solid state maser of the type described above.

More specifically, an object of the invention is to provide a device employing magnetomechanical means to continuously furnish an excess upper state electron spin population in a paramagnetic material for continuously amplifying electromagnetic energy by stimulated emission.

Another object of the invention is to provide means, in a solid state maser, for producing a magnetic field profile on moving paramagnetic material which will create an excess electron spin population in an upper of two energy levels.

Another object of the invention is to provide a solid state maser employing an endless tape of paramagnetic material, or an endless tape having paramagnetic material placed thereon or combined therein to facilitate

2

continuously applying to the resonant cavity an excess electron spin population in an upper energy state.

A still further object of the invention is to provide a solid state maser employing a fluid containing paramagnetic material, and circulating through a closed path, to facilitate furnishing an excess electron spin population in the upper of two energy levels.

A still further object of the invention is to provide a solid state maser which operates superregeneratively.

The above and other objects and features of the invention will become apparent from the following detailed description taken in connection with the accompanying drawings which form a part of the specification and in which:

FIGURE 1 is a graphical illustration of the operation of the present invention;

FIG. 2 is an illustration of one embodiment of the invention. Another version of a maser employing a rotating disc is described in a copending abandoned application, Serial No. 656,092;

FIG. 3 is a sectional view taken along line III—III of FIG. 2;

FIG. 4 is a sectional view taken along line IV—IV of FIG. 2;

FIG. 5 is a sectional view taken along line V—V of FIG. 2;

FIG. 6 is an illustration of the preferred embodiment of the invention;

FIG. 7 is a sectional view taken along line VII—VII of FIG. 6;

FIG. 8 is a top view of another embodiment of the invention;

FIGS. 9A and 9B are cross-sectional views taken along lines IXA—IXA and IXB—IXB, respectively, of FIG. 8;

FIG. 10 is an illustration of the invention which operates superregeneratively;

FIG. 11 is a graph illustrating a magnetic field profile traversed by the paramagnetic material in the embodiments of the invention outlined above as a function of time or distance; and

FIG. 12 is a graph illustrating the radiation density in the resonant cavity of the superregenerative embodiment of the invention shown in FIG. 10, as a function of time.

Referring to FIG. 1, two energy states of electron spins in a paramagnetic material are indicated by the horizontal lines identified as E_1 and E_2 . Part of the electron spins in the paramagnetic material will be at the lower energy state E_1 while the remainder will be at the higher energy state E_2 . The paramagnetic material is in thermal equilibrium, corresponding to a normal or relaxed condition, when there is an excess electron spin population in the lower energy state E_1 . Electron spins in the energy states E_1 and E_2 can interact with a microwave radiation field of appropriate frequency and either absorb energy from the radiation field while advancing to a state of greater energy or, under the influence of the radiation field, can give up some of their energy and drop to a state of lower energy. The amount of energy thus transferred (i.e., $E_2 - E_1$) is related to the frequency of the radiation field by the following equation:

$$E_2 - E_1 = hv$$

where h is Planck's constant and v is the frequency.

If an electron spin in the lower energy state E_1 is placed in a microwave field of appropriate frequency, it will absorb energy and advance to the upper energy state E_2 . An electron in the upper state E_2 , on the other hand, will give up energy to the microwave field and drop to the lower state E_1 . The probability for either transition is the same. Therefore, whether a system of many electrons exhibits a net absorption or emission of energy de-

pends upon whether more electrons are in the lower or upper energy state. All such systems when allowed to come to thermal equilibrium (i.e., are relaxed) have more electron spins in the lower energy state E_1 and, hence, are absorptive.

In order for the paramagnetic material to be emissive and release energy, there must be an excess of electron spins in the upper energy state E_2 . An excess population in the upper state may be produced in the following way: First, a magnetic field is applied across the paramagnetic material to establish an energy difference between the electron spin states. After a time determined by the spin-lattice relaxation time, an excess electron spin population exists in the lower state. A sufficiently rapid reversal of an external magnetic field will invert the energy levels of the electrons such that the excess spin population now appears in the upper energy level E_2 . If the paramagnetic material with an excess spin population in the upper state is now passed through a resonant cavity and if electromagnetic energy F of a predetermined frequency is fed to the cavity, the electron spins in the upper state will release their energy, resulting in amplification of the incident wave energy to produce an amplified signal F' .

A maser for amplifying electromagnetic energy by the process described above is shown in FIG. 2 and comprises a disk 10 of paramagnetic material, or containing some paramagnetic atoms or molecules, which is made to rotate about an axis 12. If preferred, only the outer periphery of disk 10 need be formed from paramagnetic material. A portion of the periphery of disk 10 lies between the opposite poles of a C-shaped electromagnet 14 which applies a steady magnetic field to the paramagnetic material and which has claws at the end thereof as shown in FIG. 5. At the same instant another portion of the periphery of disk 10 lies in a resonant cavity 16 which is located between the opposite poles of a second C-shaped electromagnet 18 which produces a field which is reversed with respect to the field produced by magnet 14, magnet 18 having claws at the end thereof as shown in FIG. 5. Electromagnetic energy is fed to the resonant cavity 16 through wave guide 20 and leaves the resonant cavity through the same wave guide or through another wave guide 22. From point A to point B, while the magnetic material is under the influence of the field produced by magnet 14, the electron spins spend a long enough time to come almost to equilibrium in the strong field produced by magnet 14. The time spent in magnet 14 may be reduced considerably by the use of techniques for reducing T_1 , where T_1 is the spin-lattice relaxation time. One technique applies to those substances, e.g. doped silicon, which, when illuminated with light, release free carriers. Under such circumstances, T_1 can be reduced to the order of a microsecond. A second technique for reducing T_1 applies to those substances, e.g. paramagnetic salts, in which a "doping" agent can be used in such a way as to introduce a degeneracy in energy level spacings between the host system and doping system for certain values of field or orientation. This produces an excess f of spins in the lower energy state E_1 where

$$f = \frac{N_{\text{lower}} - N_{\text{upper}}}{N_{\text{lower}} + N_{\text{upper}}} \text{ and } \frac{N_{\text{lower}}}{N_{\text{upper}}} = \exp \frac{gu_0 H_B}{kT}$$

and where

g is the splitting factor for the electron;

u_0 is the Bohr magneton;

k is Boltzmann's constant; and

T is the absolute temperature.

Between points B and E shown in FIG. 2, an electron experiences a rapid reversal of magnetic field. This process inverts the energy levels of the electron spins and results in the excess population now being in the upper state E_2 . The electrons then proceed into the micro-

wave cavity 16 in the section F to G. The cavity is in the uniform steady magnetic field produced by magnet 18 and the magnitude of this field determines the frequency at which the electron spins will release their energy.

The magnetic field experienced by the paramagnetic material as it passes through the fields produced by magnets 14 and 18 is shown in FIG. 11. Between points A and B, the paramagnetic material is under the influence of the strong magnetic field H_B produced by magnet 14. Between points B and E in FIG. 11, the field experienced by an electron is rapidly reversed since the paramagnetic material passes rapidly from magnet 14 to magnet 18. Consequently, the minimum effective field H' , is reversed in a time, $T_{H'}$, that is short compared to the Larmor period $L_{H'}$, in that field. The "minimum effective field" is the smallest field capable of lining up the electron spins. That is, it is roughly a field several times larger than the half width of the resonance line. This process inverts the energy levels of the electron spins and results in the excess population now being in the excited state, as was explained above. The spins then proceed into the microwave cavity 16 between F and G, during which time the paramagnetic material is under the influence of the uniform steady magnetic field H_R , the magnitude of which determines the frequency, V , of emission. Stimulated emission takes place in the cavity, with the result that the electromagnetic energy fed into the cavity from wave guide 20 is amplified and leaves the cavity either back through guide 20 or through wave guide 22. Provided that the time taken from point B to point F is short compared with the spin-lattice relaxation time, the efficiency of the process is high and not many excited spins are relaxed by interaction with the lattice during the time from B to F. After leaving the cavity, the spins proceed to electromagnet 14 where the process is repeated.

As an amplifier or spectrometer the gain of the device is proportional to $NfQt/v$ where

40 N is the number of spins passing through the cavity per second;

f is the fraction defined above;

Q is the quality factor of the cavity;

v is the half-width of the resonance line; and

45 t is the transit time through the cavity.

As a microwave generator, the maximum power output is proportional to Nfv . Thus the output increases with increasing frequency and increasing peripheral speed.

50 The factors determining the minimum speed of rotation are:

(1) That $T_{H'} \ll L_{H'}$, i.e. $T_{H'} \ll 1/v_{H'}$ where

$$55 h\nu_{H'} = gu_0 H'$$

(2) That the time, T_{bf} taken from B to F be only a fraction of T_1 .

60 Assuming a field gradient at C—D of 5×10^3 gauss/cm. in the direction of motion and requiring that $T_{H'} = 0.1 L_{H'}$, it is easy to show that the required peripheral velocity, S , is given by $S = 5.6 \times 10^3 (H')^2$ cm./sec. Thus for $H' = 1$ gauss, $S = 5.6 \times 10^3$ cm./sec., which for a disc 15 cm. in diameter corresponds to about 7,000 r.p.m.

65 For the distance B to F to be 3 cms. or longer and for $T_{bf} = 0.2 T_1$, $S = 15/T_1$. Thus, in this example T_1 would have to be 3×10^{-3} seconds or longer. Increasing the speed of rotation, besides increasing N , widens the choice of working substance to materials with broader lines (larger H') and shorter relaxation times.

70 The best working substance will be a material exhibiting a sharp paramagnetic resonance line and also having a long spin-lattice relaxation time. Relaxation times of 10^{-4} seconds or longer and line widths less than 10 gauss are practical.

With materials so far reported in the literature it is mechanically just feasible to operate the device at room temperature, either as a high-gain amplifier or as a microwave generator with an output of about 0.1 watt at 3 mm. In this case the working substance could be for example 10 cc. of potassium chloride containing 10^{19} F-centers per cc. on a 30 cm. diameter disk rotating at 60,000 r.p.m., $f=0.75\%$ and $T_1=2.5 \times 10^{-5}$ seconds. Other materials, for which T_1 has not been measured at room temperature but which are expected to be an improvement on the above, are (a) diamond, boron nitride, or synthetic sapphire doped with paramagnetic impurities or containing paramagnetic centers as the result of irradiation, (b) silicon doped with lithium, arsenic, antimony, bismuth or phosphorus in any suitable concentration.

As one goes to lower temperatures, T_1 is considerably increased for all substances, so that in the above example the speed of rotation could probably be reduced to 15,000 r.p.m. at liquid nitrogen temperature and at low enough temperatures to the limit set by the non-adiabatic field reversal condition, perhaps 5,000 r.p.m.

For a microwave generator of reasonable power output it is desirable to use a substance with the largest spin density consistent with a line width less than about 10 gauss. At present it seems that heavily doped silicon (up to 10^{20} donors/cc.), diphenyl-picryl-hydrazyl (10^{21} spins/cc.) or diluted potassium chromicyanide (10^{20} spins/cc.) may prove to be the best materials for this application.

For maximum gain in an amplifier where power output is not the prime consideration, low spin density is not a disadvantage if it is accompanied by a compensating narrow line width. Materials having line widths less than one gauss and with long enough relaxation times at liquid helium temperatures are bisulphates of graphite and certain organic free radicals, as well as substances exhibiting inhomogeneously broadened lines such as doped silicon and F-centers in alkali halide crystals. These would also be chosen to minimize rotational speed when power is not the prime consideration.

The preferred embodiment of the instant invention is shown in FIGS. 6 and 7 and comprises a continuous tape 50 of paramagnetic material, or having paramagnetic material deposited thereon, which is mounted on two spaced rotating drums 52 and 54 so that the tape 50 is continuously moving. The tape moves through the field produced by a first electromagnet 56 to create an excess electron spin population in a lower energy state E_1 as was explained above. The tape then moves into the resonant cavity 58 which is under the influence of the magnetic field produced by a second electromagnet 60, the field produced by electromagnet 60 being reversed with respect to that produced by electromagnet 56. Electromagnetic energy of a predetermined frequency, determined by the strength of the magnetic field at the cavity 58 enters the cavity from waveguide 62 and, having been amplified, leaves via waveguide 64 or back through waveguide 62. The principle of operation of the embodiment of this invention is the same as that for the masses shown in FIGS. 1-5 and the magnetic field profile shown in FIG. 11 is traversed by the paramagnetic material.

A further embodiment of the invention is shown in FIGS. 8, 9A and 9B and comprises a closed fluid circuit 100 containing a fluid medium incorporating electron spins. The liquid passing through the circuit 100 may be a liquid which exhibits electron spin paramagnetism such as a liquid metal ammonia solution or it may be an inert liquid containing a solid paramagnetic material. As an alternative, it may be a paramagnetic gas, such as oxygen or the oxides of nitrogen, or it may be an inert gas carrying solid paramagnetic particles in suspension. A still further alternative would be to use a liquid refrigerant, such as liquid nitrogen, as a carrier for oxygen

or another paramagnetic gas. The fluid in circuit 100 first passes through the steady magnetic field produced by electromagnet 102 from point A to point B to create an excess electron spin population in the lower energy level E_1 . From point B to E, the fluid passes rapidly from the field produced by magnet 102 to that produced by electromagnet 104. Once in the field of magnet 104, it passes through the resonant cavity 106. Since the field produced by electromagnet 104 is reversed with respect to that produced by magnet 102, an excess electron spin population is produced in the higher energy level E_2 , and electromagnetic energy entering cavity 106 from waveguide 108 leaves the cavity as amplified wave energy via waveguide 110 or 108.

An embodiment of the present invention which operates superregeneratively is shown in FIG. 10. This embodiment of the invention operates upon a principle similar to that shown in FIGS. 1-5 and comprises a disk 210 which rotates about an axis 212. The periphery of the disk, as was the case with the masses shown in FIGS. 1-5, first passes through the magnetic field produced by electromagnet 214 and then passes through the resonant cavity 216 which is situated in the magnetic fluid produced by electromagnet 218, the field produced by magnet 218 being reversed with respect to that produced by magnet 214. Electromagnetic wave energy enters the cavity 216 via waveguide 220 and leaves as amplified wave energy via waveguide 222 or 220.

In FIG. 10 the paramagnetic material is placed around the periphery of the rotating disk 210 in discrete and separate sections 224. For a disk which is 15 centimeters in diameter, 100 or more sections 224 of paramagnetic material could be equally spaced around the periphery of the disk. The sections must be widely enough spaced so that only one section can be in the cavity 216 at a given time, and so that the radiation density in the cavity due to one section has fallen to a low enough level before the arrival of the next section. When the density of spins in any section is greater than that necessary to cause oscillation build-up in the cavity due to noise or incoming signal, the device can operate superregeneratively.

The operation of the superregenerative maser shown in FIG. 10 is graphically illustrated in FIG. 12. It can be seen that the radiation density builds up as each section 224 passes through the cavity and then subsides before the next section passes through the cavity. In this way, each time a section leaves the cavity oscillation build-up is terminated.

The amplitude of oscillation after a given time interval depends in a definite way upon the magnitude of the radiation of the proper frequency present during the sensitive portion of the cycle. In FIG. 12 the build-up of oscillation with noise alone in the cavity during the sensitive portion of the cycle (shaded area) is compared with that with noise plus signal. For a disk rotating at a thousand revolutions per second, the quench frequency or pulse repetition rate will be of the order of 100 kilocycles. This can be improved by spacing the sections 224 more closely around the periphery of the disk 210. Quenching, or cut-off, comes about automatically because of the mechanical removal of the section from the cavity.

Although the invention has been shown in connection with a certain specific embodiment, it will be readily apparent to those skilled in the art that various changes in form and arrangement of parts may be made to suit requirements without departing from the spirit and scope of the invention.

We claim as our invention:

1. Apparatus for amplifying electromagnetic wave energy of predetermined frequency by stimulated emission of radiation comprising, in combination, a continuously moving tape member moving in a predetermined

path and having paramagnetic material continuously disposed along the length thereof, said tape member moving at a predetermined speed, said paramagnetic material having two discrete energy levels of electrons, said electrons undergoing transitions between said two energy levels when subjected to electromagnetic wave energy of said predetermined frequency, first magnetic field producing means disposed in predetermined position with respect to a first portion of said path for subjecting the paramagnetic material on the adjacent portion of the tape to a first magnetic field of predetermined magnitude and direction, second magnetic field producing means disposed adjacent the first magnetic field producing means and in predetermined position with respect to a second portion of said path, said portion of the tape moving from the first portion of the path substantially directly to the second portion of the path, the second magnetic field producing means producing on said portion of the tape while said portion is adjacent thereto a second magnetic field of predetermined magnitude and of a direction opposite to the direction of the first magnetic field, the speed of movement of said tape being such that any point on the tape moves from the first magnetic field to the second magnetic field in a time which is short compared to the Larmor period of the paramagnetic material, the sudden reversal of the polarity of the magnetic field on the paramagnetic material as the paramagnetic material on the tape moves from the first magnetic field to the second magnetic field causing state preparation in the paramagnetic material with an excess of electrons having high energy spin states and occupying the upper of said two energy levels, resonant cavity means resonant at said predetermined frequency disposed in predetermined position with respect to a portion of the path of said tape and in predetermined position with respect to said means for producing a second magnetic field, said tape passing through said resonant cavity means, and means connected to the resonant cavity means for supplying electromagnetic wave energy to be amplified to the resonant cavity means and conducting electromagnetic wave energy from the resonant cavity means, said portion of said tape passing through said resonant cavity means before spin-lattice relaxation occurs in the paramagnetic material in said portion of said tape, at least some of the electrons with high energy spin states in the paramagnetic material while in the resonant cavity means giving up energy to the electromagnetic wave of predetermined frequency as said last named electrons revert to the lower energy level thereby amplifying said electromagnetic wave, the continuous movement of paramagnetic material through the first and second magnetic fields as the tape moves providing continuous state preparation and providing for continuous amplification of said electromagnetic wave energy.

2. Apparatus for amplifying electromagnetic wave energy having a predetermined frequency by stimulated emission of radiation, comprising, in combination, a continuously moving tape member moving in a predetermined path and having paramagnetic material continuously disposed along the length thereof, said tape member moving at a predetermined speed, said paramagnetic material having two discrete energy levels of electrons, the electrons of the paramagnetic material undergoing transitions between said two energy levels when subjected to electromagnetic wave energy of said predetermined frequency, first magnetic field producing means disposed in predetermined position with respect to a first portion of said path for subjecting the paramagnetic material on the adjacent portion of the tape to a first magnetic field of predetermined magnitude and direction, said speed being selected whereby any minute area of the tape remains in said first magnetic field for a period of time sufficient to induce substantially complete relaxation of electrons in the paramagnetic material

therein, second magnetic field producing means disposed adjacent the first magnetic producing means in predetermined position with respect to a second portion of said path, said area of the tape moving from the first portion 5 of the path substantially directly to the second portion of the path, the second magnetic field producing means producing a second magnetic field of predetermined magnitude and of a direction opposite to the direction of said first magnetic field, said area moving from the 10 first magnetic field to the second magnetic field in accordance with the speed of movement of the tape in a time short compared to the Larmor period of the paramagnetic material, the passage of the paramagnetic material from the first magnetic field to the second magnetic field whereby the paramagnetic material undergoes a sudden field reversal causing state preparation in the paramagnetic material with an excess of electrons having high energy spin states and occupying the upper of said two energy levels, resonant cavity means resonant 15 at said predetermined frequency disposed in predetermined position with respect to a portion of the path of said tape, and means for conducting electromagnetic wave energy of said predetermined frequency to and from said resonant cavity means, said area of said tape 20 passing through said resonant cavity means before spin-lattice relaxation occurs in the paramagnetic material in said area, at least some of the electrons with high energy spin states in the paramagnetic material while in the resonant cavity means giving up energy to said 25 electromagnetic wave of predetermined frequency as said last named electrons revert to the lower energy level thereby amplifying said electromagnetic wave, the continuous movement of paramagnetic material through the first and second magnetic fields as the tape moves 30 providing continuous state preparation and providing for continuous amplification of said electromagnetic wave energy.

3. Apparatus for amplifying electromagnetic wave energy having a predetermined frequency in a predetermined portion of the electromagnetic wave energy spectrum by stimulated emission of radiation comprising, in combination, a conduit having a paramagnetic fluid medium continuously passing therethrough, said paramagnetic fluid medium having two discrete energy levels of electrons, the electrons of said paramagnetic fluid medium undergoing transitions between said two energy levels when subjected to electromagnetic wave energy of said predetermined frequency, means disposed in predetermined position with respect to a first portion of 40 said conduit for subjecting the fluid medium in the first portion of the conduit to a first magnetic field of predetermined magnitude and direction, means forming a resonant cavity for electromagnetic wave energy of said predetermined frequency disposed in predetermined 45 position with respect to a second portion of said conduit 50 whereby said cavity is in the path of said moving fluid medium, means for subjecting said resonant cavity and the fluid medium passing therethrough to a second magnetic field of predetermined magnitude and which is 55 reversed in direction with respect to said first magnetic field, any portion of the fluid medium moving from the first magnetic field to the second magnetic field in a time which is short compared to the Larmor period of the paramagnetic material, the sudden magnetic field polarity reversal on the paramagnetic fluid medium as it 60 moves from the first magnetic field to the second magnetic field causing state preparation with an excess of electrons having high energy spin states and occupying the higher of said two energy levels, and means for conveying electromagnetic wave energy of said predetermined frequency to and from said resonant cavity, at least some of the electrons with high energy spin states 65 in the fluid medium in the resonant cavity giving up energy to the electromagnetic wave before spin-lattice relaxation occurs in the paramagnetic material as said 70 75

last named electrons revert to the lower of said two energy levels thereby amplifying said electromagnetic wave of predetermined frequency, the continuous movement of the paramagnetic fluid medium through the first and second magnetic fields providing continuous state preparation and providing for continuous amplification of said electromagnetic wave energy.

4. Apparatus according to claim 3 in which the paramagnetic fluid medium is disposed in a circulating fluid refrigerant for maintaining the paramagnetic material at a temperature approaching absolute zero to thereby increase the spin-lattice relaxation time of the paramagnetic material.

5. Apparatus for amplifying electromagnetic wave energy of a predetermined frequency by stimulated emission of radiation comprising, in combination, a conduit having a paramagnetic fluid medium therein, pump means connected to the conduit, said conduit and pump means forming a continuous path for the flow of said paramagnetic fluid medium, said paramagnetic fluid medium having two discrete energy levels of electrons, said electrons undergoing transitions between said two energy levels when subjected to electromagnetic wave energy of said predetermined frequency, means disposed in predetermined position with respect to a first portion of said conduit for subjecting the fluid in said first portion of the conduit to a first magnetic field of predetermined magnitude and direction, means forming a resonant cavity resonant at said predetermined frequency and disposed in predetermined position with respect to a second portion of said conduit adjacent said first portion whereby said cavity is in the path of said moving fluid medium, the fluid medium passing into said second portion after passing through the first portion, means for subjecting said resonant cavity and the fluid medium passing therethrough to a second magnetic field of predetermined magnitude and which is reversed in direction with respect to said first magnetic field, the speed of flow of the paramagnetic fluid medium being such that the fluid medium passes from the first portion of the conduit to the second portion of the conduit in a time short compared to the Larmor period of the paramagnetic material, the sudden reversal of the direction of the magnetic field causing state preparation in the paramagnetic fluid medium with an excess of electrons having high energy spin states and occupying the higher of said two energy levels, and means for conveying wave energy of said predetermined frequency to and from said resonant cavity, at least some of the electrons with high energy spin states in the fluid medium in the resonant cavity giving up energy to the electromagnetic wave before spin-lattice relaxation occurs in the paramagnetic material as said last named electrons revert to the lower of said two energy levels thereby amplifying said electromagnetic wave, the continuous movement of the paramagnetic fluid medium through the first and second magnetic fields providing continuous state preparation and providing for continuous amplification of said electromagnetic wave energy.

6. In apparatus for superregeneratively amplifying electromagnetic wave energy of predetermined frequency by stimulated emission of radiation, in combination, a continuously moving material moving at a predetermined speed, discrete similar sections of a paramagnetic material carried at substantially equally spaced intervals by said moving material, said paramagnetic material having two discrete energy levels of electrons, said electrons undergoing transitions between said two energy levels when subjected to electromagnetic wave energy of said predetermined frequency, first magnetic field producing means disposed in predetermined position with respect to the moving material for subjecting the sections of paramagnetic material carried by the moving material to a transverse magnetic field of predetermined direction and magnitude as the sections move into position adjacent the first magnetic field producing means, second magnetic

field producing means adjacent the first field producing means for subjecting said moving material and paramagnetic sections to a second magnetic field of predetermined magnitude reversed in polarity from the first magnetic field, any discrete section of said paramagnetic material moving from the first magnetic field to the second magnetic field in a time short compared to the Larmor period of the paramagnetic material, the sudden reversal of the polarity of the magnetic field on the paramagnetic material of said last named discrete section causing state preparation in the paramagnetic material of said last named section with an excess of electrons having high energy spin states and occupying the higher of said two energy levels, means forming a resonant cavity positioned within the second magnetic field and in predetermined position with respect to the continuously moving material whereby the discrete sections of paramagnetic material are carried through the resonant cavity while subjected to the second magnetic field, said cavity being resonant at said predetermined frequency, and means for conducting electromagnetic wave energy of said predetermined frequency to and from said resonant cavity, at least some of the electrons with high energy spin states in the discrete paramagnetic section in the resonant cavity giving up energy to the electromagnetic wave before spin-lattice relaxation occurs in the paramagnetic material of the last named section, the density of the electrons with high energy spin states in the discrete paramagnetic sections being greater than that necessary to cause oscillation build up in the cavity due to noise and a signal of said predetermined frequency, the speed of movement of the continuously moving material being preselected whereby said last named discrete section of paramagnetic material moves out of the resonant cavity after a predetermined time interval to provide for damping of electromagnetic wave energy developed in said cavity while the discrete section was disposed therein.

7. In apparatus for superregeneratively amplifying electromagnetic wave energy of predetermined frequency by stimulated emission of radiation, the combination of a rotating disc rotating at a predetermined speed, a plurality of similar discrete sections of paramagnetic material carried on the outer periphery of said rotating disc at substantially equally spaced intervals, said paramagnetic material having two discrete energy levels of electrons, said electrons undergoing transitions between said two energy levels when subjected to electromagnetic wave energy of said predetermined frequency, first magnetic field producing means for subjecting said disc and the paramagnetic sections carried thereby to a first transverse magnetic field of predetermined direction and magnitude, second magnetic field producing means disposed adjacent the first magnetic field producing means in the path of the rotating disc for subjecting the paramagnetic sections to a second magnetic field of predetermined magnitude and reversed in direction from the first magnetic field, any paramagnetic section moving from the first magnetic field to the second magnetic field in a time which is short compared to the Larmor period of the paramagnetic material, the sudden reversal of the direction of the magnetic field on said paramagnetic material causing state preparation with an excess of electrons with high energy spin states and occupying the higher of the two energy levels, a resonant cavity resonant at said predetermined frequency located in said second magnetic field, said rotating disc passing through said resonant cavity, and means for conducting electromagnetic wave energy of said predetermined frequency to and from said resonant cavity, at least some of the electrons with high energy spin states in the discrete paramagnetic sections giving up energy to the electromagnetic wave before spin-lattice relaxation occurs in the material, the density of the electrons with high energy spin states in the discrete paramagnetic sections being greater than that necessary to cause oscillation build up in the cavity due to noise

and a signal of said predetermined frequency, said disc rotating at said predetermined speed whereby any discrete section of paramagnetic material remains in the resonant cavity a predetermined time interval and is moved out of the resonant cavity to provide damping of the build-up of electromagnetic wave energy in the resonant cavity at a predetermined level of energy build-up, the build-up of energy in the resonant cavity as discrete sections of paramagnetic material move through the cavity providing for superregenerative pulsed amplification of the signal of said predetermined frequency.
